UNITED STATES PATENT OFFICE.

CHARLES JARECKI, OF ERIE, PENNSYLVANIA.

OIL-SAVER FOR OIL-WELLS.

SPECIFICATION forming part of Letters Patent No. 224,090, dated February 3, 1880.

Application filed September 1, 1879.

To all whom it may concern:

Be it known that I, CHARLES JARECKI, of Erie, in the county of Erie and State of Pennsylvania, have invented a new and useful Oil-Saver for Oil-Well; and I do hereby declare the following to be a full, clear, and exact description thereof.

My invention relates to the construction of a device to be applied within the casing-head of an oil or other deep-bored well, whereby the operation of boring the well can be continued after the oil or other desirable product is reached without wasting said product or endangering the safety of the operators and rig by the escaping gas and oil becoming ignited.

In boring oil-wells the tools and connecting-cable operate through the bore of a large pipe called a "casing." On the top of this casing is what is called a "casing-head," which is provided with means for attaching branch pipes for conveying away the gas or oil which may come up during the operation of boring and after the well is finished.

My device consists of a two-part ring or cap which will clamp around the cable and be seated in the top of the casing-head, and will permit the cable to move freely through it during the operation of drilling. The opening through this ring or cap in which the cable moves is made flaring or tapering, and when it is desired to shut off the flow of gas or oil from below a wrapping is put around the cable and is drawn into the ring by the weight of the tools, and thus completely stuffs or closes that opening and forces the oil or gas through the branch opening in the casing-head.

In drilling oil-wells gas is often found some time before the oil-vein is reached; but the cable sufficiently closes the opening in the ring to prevent any very great volume of it from escaping at that point, and the gas finds its way through the branch openings and is usually conducted through pipes to the boiler-furnace; but when oil is reached it is desirable to save it, and as it is necessary to drill some distance below the vein the work of drilling has to proceed while the oil is flowing from the well. The flow of oil is, however, periodical and not continuous, and hence when a flow occurs the operator can wrap the cable

and let the wrapping draw down into the flaring mouth of the ring and entirely shut off the flow of oil through the ring past the cable. Of course the work of drilling stops during the flow; but as soon as that stops, which is soon the case, the work of drilling can at once be proceeded with.

Other devices have been heretofore invented for this purpose. (See Patents No. 129,129, July 16, 1872, to V. Gretter, and No. 200,471, February 19, 1878, to E. J. Northrup.)

My invention therefore consists in an improved construction of the ring or cap.

My device is illustrated in the accompanying drawings, as follows:

Figure 1 is an elevation view of the top of the casing, the casing-head, and the cap. Fig. 2 is a vertical section of the same parts. Fig. 3 is a top view of the cap and the casing-head. Fig. 4 is a side view, from the right, of the parts shown in Fig. 3.

The letters of reference indicate parts as follows: A is the casing-head. B is the two-part ring or cap. C C are the clamping-bolts for holding the two parts of the cap together. D is the cable. E is the casing. F F are the branch openings from the casing-head. G is the wrap, which is placed on the cable to close the orifice in the cap. b b are set-screws for holding the cap on its seat in the casing-head. c c c are arms extending from the cap, and which, together with the clamp-bolts C C, form the clamping device by which the two parts of the ring or cap are held together.

The casing and casing-head may be of ordinary construction.

The ring or cap B is in two parts and doweled together, (see dowel-holes d in Fig. 2,) with dowels fixed in one part and entering dowel-holes in the other part. These two parts are provided with means for clamping them together around the cable.

The object in having the ring in two parts, with means for clamping them together, is to enable the operator to attach the device without removing the cable and tools from the well.

The clamping device which I herewith show consists of two swinging bolts, C, pivoted in the arms c of one of the parts of the cap B, and swinging into openings in the arms c of the other part, and provided with binding-

nuts which screw up against the outer face of the last-mentioned arms. I do not, however, desire to be limited to this precise means of clamping the two parts together, as many other devices for the same purpose will readily suggest themselves to a mechanic.

The mouth of the orifice in the ring through which the cable passes is made flaring; and to tightly close it, so as to prevent the passage of oil past the cable, I wrap the cable with a cloth or any suitable object, and then allow the tools to settle down a little, so as to draw this wrapping into the flaring mouth of the orifice, which closely packs it around the cable and entirely stuffs the opening. (See G in Fig. 2.) When thus arranged, as shown in Fig. 2, no oil can escape past the cable, but must find its way out through the branch openings F.

This mode of stuffing the cable-opening is very simple and effective. I do not, however, claim it as my invention, as I believe it has been heretofore used.

I am aware that in the patent to G. Finton, September 30, 1873, No. 143,280, it is stated

that one of the plates (of which there are two) 25 which close the top of the casing may be made in two parts; but such a construction is not my invention, for my invention consists in making the whole device which sets in the casing-head bisected, so that it can be attached 30 and detached while the cable is pendent in the well, and no such result can be effected by the device shown in Finton's patent.

What I claim as my invention is—

An oil-saving device for oil-well casing- 35 heads formed of two parts and provided with a clamp whereby said parts can be clamped together, thereby permitting the adjustment of said device in the casing-head and upon the cable while said cable is pendent in the well, 40 substantially as and for the purposes set forth.

In testimony whereof I, the said CHARLES JARECKI, have hereunto set my hand.

CHARLES JARECKI.
